CLAIM

The ornamental design for a built-in coffee apparatus, as shown and described.

DESCRIPTION

FIG. 1 is a perspective view of a built-in coffee apparatus showing my ornamental design;

FIG. 2 is a front plan view of the built-in coffee apparatus embodiment shown in FIG. 1;

FIG. 3 is a front plan view of the built-in coffee apparatus embodiment shown in FIG. 1;

FIG. 4 is a partial front perspective view thereof, shown enlarged and broken away for ease of illustration;

FIG. 5 is a perspective view of the built-in coffee apparatus embodiment shown in FIG. 1;

FIG. 6 is a perspective view of the built-in coffee apparatus embodiment shown in FIG. 1; and,

FIG. 7 is a perspective view of the built-in coffee apparatus embodiment shown in FIG. 1.
